4 Claims. (Cl. 330—43)

ABSTRACT OF THE DISCLOSURE

The invention pertains to a traveling wave interaction device having a plurality of individually energized collector electrodes extending along the interaction path. Precise phase control of propagating electromagnetic signals is realized by means of the control of the electrical length of the slow wave propagating structure before the electron beam is completely collected. The energizing means for the individual collector electrodes may comprise a system of preprogrammed digitalized voltages from a computer. Numerous embodiments including circumferentially and longitudinally staggered electrodes adjacent to the slow wave propagating structure as well as split electron beam devices are described.

This invention relates to electronic devices and in particular to a traveling wave type device for providing controlled phase shift of an input signal.

Basically, a traveling wave tube comprises a wave propagating structure, such as a helix, and an electron beam traveling near the structure with a velocity very near the velocity of propagation of a wave on the wave structure. An electromagnetic signal is supplied to one end of the helix in the form of a traveling wave having a strong component of electric field parallel to the direction of electron beam motion. By means of continuous interaction between the electric field on the electromagnetic wave and the electron beam, amplification is obtained. The amplified electromagnetic signal is removed from the end of the helix furthest removed from the source of the electron beam.

It is frequently desirable, for example, in phased array applications to control or alter the relative phase shift of signals applied to the helix. It has been found that the degree of phase shift through the wave propagating structure is a function of the reactive loading of the electron beam and hence the beam current. Beam current may be controlled by introducing a control element at or near the source of electrons or through control of the beam collector voltage. However, phase shift versus either beam current or control element voltage characteristics have considerable nonlinearity over the useful dynamic ranges and frequency bandwidths contemplated. Thus, in precision traveling wave phase shifters based on beam current control, it is necessary to employ an external feedback system at increased cost and complexity thereby rendering the use of such devices less attractive commercially.

Accordingly, it is an object of the present invention to provide a traveling wave tube phase shifting device with inherent precision phase control without the aid of an external feedback loop.

It is a further object of the invention to provide a phase shifter having negligible hysteresis and excellent reseatability.

Still another object of the invention is to provide a precision phase shifter having characteristics capable of being duplicated from unit to unit in production.

These and other objects of the invention are provided by a traveling wave device which, in accordance with the invention, is comprised of a wave propagating structure

2

adapted to support an electromagnetic signal; a source of electrons, such as an electron gun, for transmitting a beam of electrons in proximity to said wave propagating structure; and a plurality of collecting electrodes disposed adjacent the length of said wave propagating structure and adapted to be energized by an appropriate voltage at predetermined electrodes to permit collection of substantially all of the electrons on the beam at predetermined collector electrodes. In this manner, the degree of phase shift of the input electromagnetic signal becomes proportional to the length of wave propagating structure traversed by the beam before being completely collected. Since this length can be predetermined with great accuracy, the desired degree of precision without feedback becomes a reality.

Other objects, features and advantages of the present invention will be better understood by the following description, taken together with the accompany drawings in which:

FIG. 1 is a schematic view of a traveling wave tube embodying the phase shift collecting elements of the invention;

FIG. 2 is a graph plotting the R.F. voltage versus the collecting element terminals for a predetermined frequency signal F_0 ;

FIG. 3 is a schematic view of a portion of the traveling wave tube of FIG. 1 modified to illustrate the staggered arrangement of collector electrodes; and

FIG. 4 illustrates a split beam embodiment of the invention.

Referring more particularly to FIG. 1, there is shown a traveling wave tube 11 having a helical slow wave structure 12 aligned approximately coaxially within and supported by, for example, a glass envelope 14. At one end of the tube an electron gun 16 is disposed. The gun is adapted to project a stream of electrons 17 along the longitudinal axis of the helix 12 to a collector electrode 18. A magnet, not shown, is normally provided coaxial to the tube to focus the beam. Input means 29 and output means 22 are provided for coupling electromagnetic energy onto and off from, respectively, the slow wave structure. The velocity of the electron stream and the ratio of the circumference to the pitch of the helix are such as to permit a cumulative electromagnetic interaction between the electron stream or beam 17 and the electromagnetic energy on the helix whereby the electromagnetic energy is amplified. Voltage from source V_2 , impressed across the cathode 19 of electron gun 16 and collector electrode 18, establishes a fixed beam current therebetween. A control anode 24, in the electron gun 16, controls the magnitude of the beam current and thereby the gain or amplification of the tube. The voltage on the control anode 24 is supplied from variable voltage source V_1 . It has been found that variation of the beam current not only changes the gain of the tube but likewise varies the reactive load of the wave propagating structure and hence the degree of phase shift of the signal through the structure. Furthermore, the phase shift versus actuating voltage characteristics of beam current phase shifters is inherently non-linear without external feedback loops. In order to control the degree of phase shift through the structure in a manner which is relatively independent of beam current and which is capable of a high degree of precision and linearity, there has been provided, in accordance with the invention, a plurality of collecting electrodes designated T_1-T_n , wherein n is any number greater than 1 within the limits imposed by the longitudinal length of the electrode surface, the length of the helix and the spacing required between electrodes. These electrodes T_1-T_n are spaced apart from and ad-

jacent the longitudinal axis of the helix 12. The individual collecting electrodes T_1-T_n are appropriately energized with predetermined voltages in accordance with the degree of phase shift desired so that substantially all of the electrons on the beam are collected at specified collecting electrodes thereby terminating the interaction at either one specified electrode or at certain electrodes and hence precisely establishing the degree of phase shift introduced on the signal propagated through the tube. The phase shift is thus made proportional to the length of slow wave structure passed by the beam before being substantially completely collected. For a given tube length and collecting surface the precision of the phase shifter is limited only by the closeness of spacing between the collecting electrodes. It is, therefore, within the contemplation of this invention to locate collecting electrodes circumferentially and longitudinally staggered about the helix to increase the permissible spacing tolerance between collector electrodes.

FIG. 3 shows a portion of the traveling wave tube of FIG. 1 in which the collecting electrodes are oppositely staggered. Electrodes T_2 , T_3 and T_4 are disposed in a column in the same locations as the corresponding electrodes in FIG. 1, whereas electrodes T_{2A} and T_{3A} in a second column are oppositely disposed and longitudinally staggered from electrodes T_2 , T_3 and T_4 . Several such columns may be provided about the circumference of the tube as desired.

It is also within the contemplation of the invention that the electron beam 17 may be directed so as to pass outside the helix instead of centrally through the helix as shown in FIG. 1. It is further contemplated that with the beam either inside or outside the helix a split beam technique may be employed to enable continued amplification by interaction with one beam and a controllable phase shift from the remaining beam. This embodiment of the invention is shown in FIG. 4. It is noted that corresponding parts in FIG. 1 have been similarly numbered in FIG. 4. It may thus be seen that the apparatus of FIG. 4 is identical to that of FIG. 1 with the exception of the control anode 46 and the split beams 40 and 42. In a split beam device, the electrons from cathode 19 are split into two beams 40 and 42 upon passage through two slits in anode structure 46. The two beams pass by helix 12 and interact with the signal on the helix in substantially the same manner as the single beam described in connection with FIG. 1. One or more of the beams may then be collected at, for example, collecting electrode T_5 , thus effectively terminating the degree of phase shift introduced by the beam collected on the signal propagating through helix 12. One or more of the split beams may be permitted to continue along the helix interacting with the signal and amplifying the phase shifted signal on the helix. Accordingly, it becomes apparent that with the split beam technique simultaneous phase shift and amplification may be achieved or amplification before phase shift or phase shift before amplification as may be desired by appropriately programming the collecting electrodes.

Many systems may be devised for energizing the electrodes such as by a computer having preprogrammed, digitalized voltages. Accordingly, the following system described in connection with FIG. 1 is meant to be exemplary thereof and should in no way be construed as a limitation on the scope of the invention. Referring back to FIG. 1 taken in connection with FIG. 2, there is shown a suitable system for energizing the collecting electrodes T_1-T_n . A waveguide cavity 32 or short circuited section is suitably connected as by a coaxial wire to a source of variable frequency signal 34. Coupling probes or loops are introduced into the cavity and are separately coupled to rectifying diodes 60-69 which are, in turn, respectively coupled to collecting electrodes

T_1-T_n . For a given frequency of input signal F_0 , the distribution of R.F. voltage picked up by the loops or probes is as shown in FIG. 2, curve A. High frequency rectifiers 60-69 hold off the voltage at each probe so that the D.C. voltage distribution at the collecting electrodes T_1-T_n is as shown in FIG. 2, curve B. The maximum of this voltage distribution is at T_4 and this will be the point at which most or all of the beam 17 is collected. The maximum of the voltage distribution can be moved by changing the frequency output of source 34, since the rate of change of position of the maximum voltage with respect to frequency change is a function of the waveguide dispersion which, in turn, is related to the frequency input.

It should be noted that preprogrammed digitalized voltages from a computer may be applied to appropriate collector electrodes in place of the phase control apparatus 44 depicted in FIG. 1. Furthermore, a larger or fewer number of steps of incremental phase shift may be obtained by applying voltages of the same or different magnitudes to a number of collectors at once. It is also noted that other suitably dimensioned wave propagating structures may be used in place of the helix shown in FIGS. 1, 3 and 4, such as, for example, interdigital lines, ladder lines and vane type lines. Accordingly, it is desired that this invention not be limited except as defined by the appended claims.

What is claimed:

1. In combination:

means for supporting an electromagnetic signal;
means for transmitting a beam of electrons in proximity to said wave propagating structure;
a plurality of columns of collecting electrodes adjacent the longitudinal axis of said wave propagating structure, adjacent columns being longitudinally staggered from each other;
and means for varying the phase of signals propagated through said wave propagating structure comprising a source of radio frequency signals coupled to a tuned cavity circuit having means for coupling rectified signals from said tuned cavity circuit to said collecting electrodes.

2. A traveling wave tube phase shifter and amplifier comprising:

a slow wave propagating structure adapted to support an electromagnetic signal;
a source of electrons;
means for amplifying said electromagnetic signal by compelling a beam of said electrons to traverse the longitudinal axis of said slow wave propagating structure in close proximity thereto and at a velocity such that interaction occurs between the beam and a signal on said structure;

means for producing a magnetic field extending parallel to the longitudinal axis of said slow wave propagating structure;

input means coupling said electromagnetic signal to an end of said wave propagating structure nearest said source of electrons;

output means for removing said electromagnetic signal from said wave propagating structure;

and phase shifter means for phase shifting said electromagnetic signal disposed intermediate said input and output means and adjacent the longitudinal axis of said wave propagating structure including a plurality of spaced collecting electrodes for collecting substantially all the electrons compelled from said source at predetermined distances along the length of said structure with said distances determined by the application of preselected individualized D.C. voltage distributions to each of said collecting electrodes.

3. The apparatus of claim 2 in which the collecting electrodes are disposed in columns adjacent the length of

said structure and adjacent columns are staggered longitudinally.

4. In combination:

a wave propagating structure adapted to support an electromagnetic signal;

a source of electrons;

amplifier means compelling at least a pair of beams

of said electrons to traverse the longitudinal axis of

said wave propagating structure in close proximity

thereto and at a velocity such that interaction occurs

10

between the beams and a signal on said structure;

input means for coupling said electromagnetic signal

to an end of said wave propagating structure nearest

said source of electrons;

output means for removing said electromagnetic sig-

nal from said wave propagating structure;

and phase shifter means intermediate said input and

5

output means for collecting all the electrons in at least one of said beams at predetermined distances along the length of said structure.
